UNITED STATES PATENT OFFICE.

CHARLES S. SCHENCK, OF NEW YORK, N. Y.

MEANS FOR CONVEYING OR TRANSFERRING COAL, &c.

SPECIFICATION forming part of Letters Patent No. 430,238, dated June 17, 1890.

Application filed October 29, 1888. Serial No. 289,424. (No model.)

To all whom it may concern:

Be it known that I, CHARLES S. SCHENCK, a citizen of the United States, and a resident of the city of New York, in the county of New York and State of New York, have invented certain new and useful Improvements in Means or Apparatus for Delivering or Transferring Coal, Grain, Sand, or other similar Material, of which the following is a specification.

My invention is an improvement in means or apparatus for delivering coal, grain, sand, or other material from vessels or other depositories, and is designed more particularly to provide a simple and comparatively inexpensive apparatus by which cargoes of coal, grain, sand, or other material may be discharged at various points of delivery or transferred in elevators or other structures, or by which ocean steamers or other vessels may be loaded or supplied with coal at a much less expense than has heretofore been possible, and whereby such substances as those above named may be handled with economy of time and labor.

The invention consists in the construction, combination, and arrangement of parts disclosed in the following specification, of which the accompanying drawings form a part, and in which similar letters of reference represent like or equivalent parts wherever found throughout the several views.

Figure 1 is a longitudinal vertical section of a coal-barge provided with my improvement. Fig. 2 is a top plan view of one of the conveyers and elevators employed by me. Fig. 3 is a transverse vertical section on the line *x x* of Fig. 1. Fig. 4 is a view of certain details of construction; and Fig. 5 is a section on the line *y y* of Fig. 1, looking toward the bow, and on an enlarged scale.

Although I have herein shown and described my invention as applied to a barge for the purpose of discharging coal therefrom, it is evident that it may be employed to advantage in unloading grain, sand, or other substances from vessels, and also for conveying material in storage-warehouses and other places, as hereinbefore stated.

Referring to Fig. 1, A represents the hull of the barge, which may be of the ordinary form and of any desired capacity. Arranged

longitudinally in the bottom of the vessel or barge A are two conveyer-troughs B, which extend, preferably, quite the full length of the hull and these troughs are carried up vertically at each end, as shown at B', and along the deck, as shown at B''. These troughs thus have approximately a rectangular form in outline, the two longer sides of the rectangle being horizontal and the shorter sides or ends being vertical. Within these troughs are conveyers C, consisting of plates c, attached to chains c', arranged to travel over suitable sprocket-wheels D³, journaled at the angles 65 of the troughs, each of said troughs forming, as shown, a continuous inclosed passage, in which the endless conveyer moves. For the purpose of illustrating these parts the side wall of the trough in Fig. 1 is removed. 70

Referring now to Figs. 1 and 2, E represents two elevators consisting of double shafts E' and E'', united at each end, which elevators correspond with the troughs in the bottom of the barge, with which they communicate, as 75 shown at G, and each of these elevators is provided with a conveyer similar to those within the chutes or troughs B, which are arranged to travel over suitable sprocket-wheels D³, placed at each end of the elevators. A 80 portion of the side walls of one of the elevators in Fig. 1 is removed, so as to show the conveyer, and the sprocket-wheel is shown in dotted lines. The elevators may extend to any desired height, and may be supported in 85 any preferred manner, the best arrangement being probably that shown in the drawings, wherein the connection between the elevators and the conveyers in the bottom of the barge is made near the stern, the elevator being 90 then carried forward and upward over the bow to the desired height.

Attached to the discharge end of each of the elevators is a spout or tube D', which may be so connected as to admit of its being 95 swung around, as shown in dotted lines, whereby the coal or other substance may be discharged either at the sides or directly in front of the barge or at the rear. This spout may be made of telescopic tubes and of any 100 desired length.

The barge-hull is provided with a series of oppositely-inclined floors H, which divide the hull at the bottom into a series of hopper-like

longitudinal compartments, each converging to the troughs B, thus causing the entire load to gravitate toward these troughs, which are provided with openings in the top controlled by gates K, each of which is provided with a rack-bar K' on the under side thereof, which is engaged by a gear-wheel L, journaled beneath the floor at the top of the trough and operated by a pinion through the agency of a shaft L², which extends above the deck, and is provided with a hand-wheel at the top, by means of which the shaft may be turned to open or close the gate. These gates are arranged to move upon rollers k, or arranged to form a movable support for the gates in any desired manner. It is obvious that the gates K anywhere along the bottom of the vessel may be opened to discharge the cargo into the trough B from any particular part of the barge or from all parts of it at once, as may seem desirable or necessary; and it is also evident that the barge may be divided transversely into separate compartments, each of which may be filled with a different substance, which may be unloaded separately, if desired.

The conveyers and elevators will be operated by a belt M, which runs from the drive-wheel M' of the engine, by which power is supplied to a pulley N upon the main shaft N', these two latter parts being shown more clearly in Fig. 5. Mounted upon the main shafts N' is a gear-wheel N², which engages with a gear-wheel O' on the counter-shaft O, and upon this counter-shaft is also mounted two clutch-pinions o o, which engage, respectively, with corresponding gear-wheels o' o', mounted upon shafts o² o², by which sprocket-wheels D D in the bottom of the elevator-shafts are operated. The clutch-pinions o o are operated or thrown in and out of connection with the gear-wheels o' o' by means of levers O² O², and by this means either one or both of the elevators may be operated at pleasure. All the parts described in this paragraph, except belt M and drive-wheel M', are shown in Fig. 5 in dotted lines. There are also mounted upon the main shaft N' clutch-pinions P P, which engage with corresponding gear-wheels P' P', mounted on shafts P² P², by which the sprocket-wheels D D in the aft end of the conveyers are operated; and, as in the case of the elevator-shafts above described, the clutch-pinions P P may be thrown in or out of connection with the gear-wheels P' P' by means of the levers R R, and thus either or both of the conveyers in the troughs B may be operated when desired.

60 The lower end of each of the elevator-shafts is in communication with one of the troughs B, as hereinbefore stated, the end of the elevator-shaft being placed just within the trough, as shown in Figs. 3 and 5, and the bottom and side of the trough being cut away and provided with a passage, as G, which empties into the base of the elevator-shaft.

The operation is as follows: The barge being filled with coal or other material, the gates K are opened by turning the hand-wheels L³ at the top of the shafts L², the gates moving easily upon the rollers k. The conveyers and elevators are then put in motion, the conveyers in the troughs B moving in the direction of the arrows S S and those in the elevator-shafts in the direction of the arrows V V. The coal is moved rapidly along the lower part of the trough B till it comes to the passages G, communicating with the elevator-shafts, when it drops into the bottom of said shafts, and is taken up by the conveyers within the elevator-shafts and carried to the top thereof, where it is injected into the spout or tube D', from which it is automatically discharged, either at the front, sides, or rear of the barge, into any receptacle prepared for it and at almost any desired altitude.

It will be understood that my invention is not limited to the use of two conveyer-troughs and two elevator-shafts, as it is evident that three or more might be employed without departing from the spirit of my invention, it being only necessary to alter the gearing so as to correspond with the number of conveyer-troughs and elevator-shafts employed. Neither is my improvement limited to any particular form of conveyer, the chain-links c and plates c' being employed only for purposes of illustration and description. It is probable that a bucket conveyer or carrier would be preferable in the elevator-shafts to the form shown, as it would not be so liable to clog while lifting coal, grain, sand, or other loose, lumpy, or granular material on a steeply-inclined trough, while for the flight-conveyer the form shown is probably the best.

In my Patent, No. 424,937, dated April 1, 1890, I describe, illustrate, and claim certain devices for opening and closing gates leading from the hold of a vessel to a trough running along its bottom. In this application I do not claim what is claimed in said patent.

Having fully described my invention, its construction and operation, I claim and desire to secure by Letters Patent—

1. A storage-vessel for coal and other substances having a series of troughs, each constituting an inclosed passage approximately rectangular in outline and having one part thereof along the floor of the hold, in combination with a series of endless conveyers traveling in said passages, a series of inclined floors H, dividing the lower part of the hold into hopper-like compartments and guiding their contents into said troughs, a series of gates opening and closing communication between said compartments and said troughs, respectively, a series of endless inclosed elevators supplied by said conveyers, gearing for driving said elevators and conveyers, and a series of spouts supplied by said elevators and serving to discharge the coal where needed, substantially as set forth.

2. The combination, in an apparatus for

conveying or transferring coal or other substances, of a storage-vessel having longitudinal hopper-like depressions in its bottom, a series of flight-conveyer troughs, as B, provided with endless conveyers, a series of elevators, as E, consisting of separate shafts E' and E'', united as shown, and provided with an endless conveyer, said elevators and conveyers being in communication and provided 5 with sprocket-wheels, by which the endless conveyers are carried, an engine and connecting-gearing consisting of a main shaft, as N', provided with a gear-wheel N'' and clutch-pinions P P, operated by levers R R, the gear-wheels P' P'', in connection with 10 which the clutch-pinions P P operate, said gear-wheels P being mounted upon the shafts P'', by which the sprocket-wheels D of the flight-conveyers are operated, and the gear- 15

wheel O', mounted upon the counter-shafts 20 O, the clutch-pinions o o, also mounted on said counter-shaft, the gear-wheels o' o'', in connection with which the clutch-pinions o o operate, said gear-wheels o' o'' being mounted upon the shafts o' o'', which operate the 25 sprocket-wheels D, by which the elevator-conveyers are carried, whereby by the proper manipulation of the levers R R and O'' O' the conveyers and elevators may be operated in pairs or all together, substantially as shown 30 and described.

Signed at the city of New York, in the county of New York and State of New York, this 24th day of October, A. D. 1888.

CHARLES S. SCHENCK.
